FOOT BALANCING MEANS

Charles P. Leydecker, Webster Groves, Mo.

Application December 12, 1938, Serial No. 245,084

11 Claims. (Cl. 36—71)

The present invention relates generally to shoes, and more particularly to means for achieving foot balance and correct position within a shoe, and a method for effecting such balance and position.

The present application comprises a continuation in part of my copending application Serial No. 194,021, filed March 5, 1938.

The present invention is predicated upon the theory that there is only one longitudinal bone arch in the foot construction when the heel bone or os calcis is raised above the plane of the forepart of the foot, the main columns or supports of which comprise the posterior portion of the plantar surface of the os calcis and the forward portion of the first metatarsal. Many authorities aver that there are three or four arches in the longitudinal dimension of the foot; but a study of the bones in the feet shows that the many bones which comprise a foot when in the just stated relationship make up one complete arch, some parts of which are concave and some parts of which are convex, but all of which contribute to the one single arch.

Modern shoe construction has resulted in the dropping of certain bones of the foot, notably the os calcis, cuboid and the fifth metatarsal, so that the rear portion of the fifth metatarsal contacts the shoe in walking at a point below a plane through the bottom of the posterior portion of the plantar surface of the os calcis and the forward portion of the first metatarsal. This, however, is not a natural position. This lowering of the enumerated bones of the feet has been caused by constructing shoes with heels, which, of course, raises the position of the os calcis relative to the forward portion of the first metatarsal.

Many devices have been devised in an effort to compensate for the position of the bones in the foot in this man-made position relative to the ground, and none of them has been singularly successful. Many have concentrated on supporting the inner side of the foot at the center of the arch by means which are generally designated arch supports, which support soft tissue.

However, few have seriously considered the outer side of the longitudinal arch and the raising of the os calcis from the plantar surface which, in the final analysis, is the primary weight carrier of the foot. Experiment has shown that the weight of the body in walking is carried from the posterior portion of the os calcis, or heel bone, which is the largest and strongest of the tarsal bones because its office is to transmit the weight of the body to the ground, as one main support

along a substantially curved line through the cuboid and the fifth metatarsal to the forward portion of the first metatarsal as the other main support. In other words, in walking, the weight of the body is distributed along the outer edge of the foot substantially in an arc of a circle from the heel bone to the forward portion of the first metatarsal. The forward portions of the fifth, fourth, third, and second metatarsal assist to only a minor degree this weight transfer from the base of the fifth metatarsal to the forward portion of the first metatarsal when the posterior portion of the plantar surface of the os calcis and the forward portion of the first metatarsal are on the same plane, but when the former is raised relative to the latter by heels their weight-shifting function increases greatly. The foot has a tendency to roll, which is a balanced movement when the heel is not maintained raised relative to the metatarsals.

Before proceeding, it should be observed here that the lower portion of the os calcis is not flat, but is rounded and normally has one tuberosity on the outer side and another forwardly on the plantar surface. To prevent all wobbling and elongating of the foot in walking, a support is necessary beneath the head of the fifth metatarsal and forepart of the plantar surface of the os calcis, for the tuberosity on the plantar surface, which is about one inch in front of the bearing surface of the os calcis, helps carry weight when shoes with heels are worn, which changes the general relationship of the bones of the foot.

As the weight is shifted forwardly in walking from the anterior portion of the os calcis to the base of the fifth metatarsal, the fifth metatarsal, which is, in effect, a marked protuberance, assists in the forward shifting thereof by contact with the walking surface. However, when the heel bone is elevated, the base of the fifth metatarsal is likewise relatively elevated and, to contact the walking surface, must drop a greater degree, which results in straining the main longitudinal arch, inasmuch as the bone structure must give to allow this unnatural ultimate position of the base of the fifth metatarsal and the forepart of the os calcis. This dropping downwardly of the rear portion of the fifth metatarsal and anterior portion of the os calcis accentuates the rolling weight distribution through the foot and results in the outward turning over of the shoe, which is one of the greatest wear points in modern shoe construction. The majority of shoes, after being worn a short while, show this overturning outwardly of the upper over the edge of the sole.

It should be observed that the position of the os calcis in a normal foot without a raise under it lies obliquely or at an angle that varies according to the height of the longitudinal arch, pointing upward at an angle of about 18° on an average. The more this angle is decreased, which decrease varies directly in proportion to heel heights, the more weight is thrown on the transverse arch, causing an undue strain on the muscles, tendons, and ligaments. In other words, the forward portion of the os calcis should be some distance from the bearing surface of the floor or ground under weight bearing. When heels are worn, the forward portion of the os calcis is lowered and there is considerable strain on the muscles, tendons, and ligaments to hold this forward portion up in relation to the shoe. When the os calcis is not supported properly in the shoe, there is a gradual weakening of all the supporting tissues, which allows the os calcis to drop.

This dropping downwardly of the forepart of the os calcis accentuates the rolling weight distribution throughout the foot and allows the arch to elongate from one-eighth to three-fourths inches according to the height of the arch at rest. When the arch is held in its normal position, the foot becomes shorter. Unless the anterior portion of the os calcis is properly supported when the os calcis is raised, the arch cannot be held in its normal position under weight bearing, and it must be continued to be supported in order to keep the foot in its correct position.

The present invention contemplates correcting the distorted action of bone structure, when shoes with heels are worn, by providing a support for the front or anterior portion of the os calcis, which will not allow it to drop under weight bearing. The holding up of the anterior portion of the os calcis will assist nature to keep the foot normal and nature will be able to strengthen the muscles, tendons and ligaments when the foot is weak. To compensate for the position of the bones in this man-made position relative to the ground, the anterior portion of the os calcis must be supported on a plane much higher than the posterior portion. As the foot distributes the weight forward as in walking, the anterior portion must be supported so that the weight will be shifted to the cuboid and the base of the fifth metatarsal very evenly without too much roll. The conventional arch supports and different kinds of balances to date have tried to support the inner side of the os calcis and, in doing this, they fail to give the foot its normal balance because the plantar surface must be supported to prevent the anterior portion of the os calcis from displacing itself downwardly.

It can be noted that nature has provided a space where the os calcis has been hollowed out on the inner side so that the nerves, arteries, and veins can pass from the plantar surface without any impingement that can interfere with their normal functions. This provision by nature allows the os calcis to be raised to the proper height, after it has been dropped, without interfering with circulation or with the nerves.

The present invention contemplates correcting this distorted action of the bone structure by providing a support for the forward portion of the os calcis and for the front and rear portions of the fifth metatarsal and the front portions of the fourth, third, and second metatarsals which will alleviate strain in the foot and save this undue overturning of the shoe outwardly.

The undue lowering of the anterior portion of the os calcis and the outside bone structure of the

foot, resultant of raising the heel relative to the forward portion of the first metatarsal, strains the whole foot structure and causes tiring of an individual prematurely. Only when the foot is properly balanced is the circulation of the blood normal and can the blood enter and leave the pedal extremities without straining the heart. There are nerves passing through the foot which transmit the proper amount of nerve impulses when the circulation is normal, and quite obviously impoverished circulation will lead to subnormal nerve impulses and resultant impaired activity of the feet. Lengthy experiments have proved that a foot housed in a shoe constructed in line with the present invention has normal blood circulation. Wearers of such shoes have been able to withstand very substantially greater strains in usage of the feet than when wearing shoes of conventional design and construction.

Therefore, an object of the present invention is to provide means for balancing a foot within a shoe to reduce bone, muscle and nerve strain, and to prevent the outward overturning of the shoe upper over the edge of the sole.

Another object is to provide a method of balancing a foot within a shoe to secure proper foot balance and proper foot position.

Another object is to provide a device for insertion within a shoe adapted to support the forward portions of the fifth, fourth, third, and second metatarsals and the base of the fifth metatarsal at predetermined levels above the sole of the shoe.

Another object is to provide a device for obtaining correct foot balance comprising a shoe insert constructed of a thickness in ratio to the heel height of the shoe in which it is to be employed.

Another object is to provide a device for insertion within a shoe which is adapted to elevate the anterior portion of the os calcis of a foot disposed within the shoe.

Another object is to provide a device for insertion within a shoe which is adapted to elevate the anterior portion of the os calcis, the base of the fifth metatarsal, and the forward portions of the fifth, fourth, third, and second metatarsals of a foot disposed within the shoe.

Another object is to provide an insert for a shoe which is adapted to strengthen the longitudinal arch of a foot disposed within the shoe, and to prevent undue outward rolling of such foot.

Another object is to provide an insert for a shoe which is adapted to support the anterior portion of the os calcis and to prevent the forward sliding of a foot disposed within the shoe.

Other objects and advantages will be apparent from the following description, taken in conjunction with the accompanying drawing, in which:

Fig. 1 is a longitudinal section through a shoe equipped with a device constructed in accordance with the teachings of the present invention, the bones of a foot being dotted in in contacting relation with the device;

Fig. 2 is a section on the line 2—2 of Fig. 1, the foot skeleton relationship being shown;

Fig. 3 is a side view of a shoe taken opposite to Fig. 1, the present invention being installed in operative relation therewith, the upper of the shoe being in section for clarity of illustration, and the bones of a foot being shown in contacting relation with the present novel device;

Fig. 4 is a section on the line 4—4 of Fig. 2;

Fig. 5 is a section on the line 5—5 of Fig. 2;

and

Fig. 6 is a section on the line 6—6 of Fig. 2. Referring to the drawing more particularly by reference numerals, there is shown a shoe 10 including an outer sole 11, an insole 12, a heel 13, and an upper 14. Within the shoe 10 there are cooperatively disposed two inserts 16 and 17 which are constructed in accordance with the concepts of the present invention.

The insert 17 is of elongated configuration and is of substantially the same construction as the insert forming the subject matter of my copending application Serial No. 194,021, filed March 5, 1938. The insert 17 differs from that of my copending application only in the termination thereof along the line 18 (Fig. 2). The insert 17 includes a plurality of layers 19, 20, 21, and 22 which are of varying lengths, as can be readily appreciated from an inspection of Fig. 3. The long top layer 19 is of a width to rest beneath the forward portions of the fifth, fourth, third, and second metatarsals of a foot within the shoe 10. The underlying layers 20, 21, and 22 are of lesser widths in order to ease the maximum height of the insert 17 to the level of the insole 12.

The insert 16, as shown, includes a plurality of layers 25, 26, 27, 28, 29, 30, 31 and 32 (Fig. 4), although the specific number of layers may vary. The layers 25—32 are of varying lengths and are disposed so that the insert 16 longitudinally includes an intermediately disposed peak (Fig. 1). The base layer 32 is disposed well back over the heel 13, whereas the superposed layers are stepped forwardly to provide a smooth inclined surface 33. The rear edges of the layers 25—32 are beveled to effect the smooth inclined surface 33. The top layer 25 is a relatively short piece and is located to receive in sustaining relation the protuberance 35 on the plantar surface of the anterior portion of the heel bone of an os calcis 36. Layers 30, 31, and 32 terminate at the rear line 18 of the insert 17, but the layers 26, 27, 28, and 29 extend forwardly over a portion of the insert 17 (Fig. 2), being cut away along the outer sides from the edge 18 of the insert 17 forwardly to permit the insert 17 to receive in supporting relation the rear portion of a fifth metatarsal 40 (Fig. 3). The layers 26, 27, 28, and 29 shelf off forwardly to provide an easement for the tissues of the foot disposed thereover.

The foot skeleton 38 is dotted in so that the bones thereof are in contacting relation with the inserts 16 and 17 and the insole 12 in order to more clearly illustrate the present invention. It is, of course, appreciated that flesh and skin separate the bones from the surface of such bearing surfaces. Figs. 1 and 3 clearly show the disposition of the os calcis 36 relative to the insert 16. The cuboid 39 finds some support on the insert 16 also. The rear portion of the fifth metatarsal 40 is supported by the insert 17 (Fig. 3). The forward portions of the fifth, fourth, third, and second metatarsals 40, 41, 42, and 43, respectively, are likewise supported by the insert 17, the insert 17 easing the aforesaid portions of the fifth, fourth, third, and second metatarsals from the highest point of the insert 17 to the level of the insole 12 (Fig. 2).

In use, the inserts 16 and 17 are disposed in a shoe against the insole 12 and beneath the sock lining (not shown). The number of layers employed for the insert 16 and the number of layers employed for the insert 17 will necessarily vary with a particular foot, but the prin-

ciple involved remains the same. The anterior portion of the os calcis 36 is positively supported by the insert 16 in a manner to assist in sustaining the integrity of the longitudinal arch. Some support is likewise lent to the cuboid 39, but the essential function of the insert 16 is the support of the forward portion of the os calcis 36. It must be emphasized here that the insert 16 is not an arch support in the present meaning of the term, as is evident from the present disclosure. The insert 17 gives positive support to the rear portion of the fifth metatarsal 40, thereby assisting to prevent breakdown of the longitudinal arch. The support of the rear portion of the fifth metatarsal 40 likewise prevents outward overturning of the shoe. The insert 17 also raises from the level of the insole 12 the forward portions of the fifth, fourth, third, and second metatarsals 40—43, respectively, which assists the weight-shifting function of these bones.

It is clear from the foregoing that the inserts 16 and 17, in supporting the several particularly mentioned bones, relieve strain on the tendons, muscles, ligaments and nerves which so often upset the complete human system. Both the longitudinal and the transverse arches are supported and allowed to function normally. The insert 16 secondarily serves as a stop to prevent a foot from sliding forwardly in the shoe. The heel is, in effect, blocked up by the insert 16, which acts as a fulcrum for the plantar facis ligaments, allowing them to contract to assist in holding up the longitudinal arch. As has been previously pointed out, undue rolling of the foot outwardly to overturn the upper of the shoe is prevented.

The inserts 16 and 17 have been described individually and as comprising a plurality of layers of material. It is contemplated as within the scope of the present invention that the inserts be of individual one-piece construction. It is further contemplated that they be consolidated into a single solid unit or that they may comprise one laminated unit, for they function as a unit. Experience has shown that the use of several elements, as shown, facilitates the securing of the proper relative thickness at critical points, but the foregoing other constructions may be expeditiously employed for certain installations. Any suitable material may be used for the construction of the inserts 16 and 17 such as leather, resilient materials, and the like. The material employed for the insert will necessarily vary with the condition of a particular foot.

It is to be understood that the foregoing description and accompanying drawing have been given by way of illustration and example, and not for purposes of limitation, the invention being limited by the claims which follow.

What is claimed is:

1. A device for supporting portions of a foot comprising means for supporting the anterior portion of the os calcis of a foot, means for supporting the base of the fifth metatarsal, and means for supporting the forward portions of the fifth, fourth, third and second metatarsals, said supporting device being of restricted extent to permit the head of the first metatarsal and the posterior portion of the os calcis to be supported by the insole of a shoe with which said device is associated.

2. A device for supporting portions of a foot comprising means for supporting the anterior portion of the os calcis, means for supporting the cuboid, said means being adapted to support the

os calcis and the cuboid in their normal arch positions, means for supporting the base of the fifth metatarsal, and means for supporting the forward portions of the fifth, fourth, third and second metatarsals, said supporting device being of restricted extent to permit the head of the first metatarsal and the posterior portion of the os calcis to be supported by the insole of a shoe with which said device is associated.

3. A device for supporting portions of a foot comprising means for supporting the anterior portion of the os calcis, said os calcis supporting means being of a thickness to maintain the anterior plantar surface of the os calcis in its normal longitudinal arch relationship, means for supporting the base of the fifth metatarsal, and means for supporting the forward portions of the fifth, fourth, third and second metatarsals, said supporting device being of restricted extent to permit the head of the first metatarsal and the posterior portion of the os calcis to be supported by the insole of a shoe with which said device is associated.

4. A device for supporting portions of a foot comprising means for supporting the anterior portion of the os calcis, means for supporting the base of the fifth metatarsal, and means for supporting the forward portions of the fifth, fourth, third and second metatarsals, said last means being of greater thickness beneath the forward portion of the fifth metatarsal than the supporting means beneath the rear portion of the fifth metatarsal, said supporting device being of restricted extent to permit the head of the first metatarsal and the posterior portion of the os calcis to be supported by the insole of a shoe with which said device is associated.

5. A device for supporting portions of a foot comprising means for supporting the anterior portion of the os calcis, means for supporting the base of the fifth metatarsal, and means for supporting the forward portions of the fifth, fourth, third and second metatarsals, said last means being of less thickness beneath the forward portion of the second metatarsal than beneath the forward portion of the fifth metatarsal, said supporting device being of restricted extent to permit the head of the first metatarsal and the posterior portion of the os calcis to be supported by the insole of a shoe with which said device is associated.

6. A device for insertion in a shoe comprising an elongated insert adapted to be disposed on the inner sole along the outer edge thereof, said insert having a portion to be disposed beneath the base of the fifth metatarsal and a portion to be disposed beneath the forward portion of the fifth metatarsal, said latter portion being of greater thickness than the former, said insert being of restricted extent to permit the head of the first metatarsal and the posterior portion of the os calcis of a foot to be supported by the insole of the shoe.

7. A device for insertion in a shoe comprising an elongated insert adapted to be disposed on the inner sole along the outer edge thereof, said insert having a portion to be disposed beneath the

base of the fifth metatarsal and a portion to be disposed beneath the forward portion of the fifth metatarsal, said latter portion being of greater thickness than the former, said latter portion being of a width to extend beneath the forward portions of the fourth, third, and second metatarsals and of decreasing thickness beneath the forward portions of the third and second metatarsals to ease weight transfer to the forward portion of the first metatarsal, said insert being of restricted extent to permit the head of the first metatarsal and the posterior portion of the os calcis of a foot to be supported by the insole of the shoe.

8. A device for supporting portions of a foot comprising means for supporting the anterior portion of the os calcis, means for supporting the cuboid, said os calcis and cuboid supporting means being adapted to positively maintain the os calcis and cuboid in normal longitudinal arch relationship, means for supporting the base of the fifth metatarsal, and means for supporting the head of the fifth metatarsal, said supporting device being of restricted extent to permit the head of the first metatarsal and the posterior portion of the os calcis to be supported by the insole of a shoe with which said device is associated.

9. In a device of the kind described, an insert adapted to be disposed in a conventional shoe comprising a portion for supporting the anterior portion of the os calcis of a foot above the plane of the insole of the shoe, said anterior portion supporting portion terminating short of the posterior portion of the os calcis so that the posterior portion of the os calcis is supported on the insole, a portion for supporting the base of the fifth metatarsal above the plane of the insole, and a portion for supporting the forward portions of the fifth, fourth, third and second metatarsals above the plane of the insole, said portion supporting the anterior portion of the os calcis being of greater thickness than the other said supporting portions.

10. An insert for disposition within a conventional shoe, said insert being of a configuration to lie beneath the anterior portion of the os calcis, the cuboid, and the fifth, fourth, third and second metatarsals of a foot, said insert providing a positive support for the anterior portion of the os calcis, the cuboid, the base of the fifth metatarsal and the forward portions of the fifth, fourth, third and second metatarsals, but being of restricted extent to permit the posterior portion of the os calcis and the head of the first metatarsal to be supported directly by the insole.

11. A device for supporting portions of a foot comprising means for supporting the anterior portion of the os calcis, means for supporting the base of the fifth metatarsal, and means for supporting the head of the fifth metatarsal, said supporting device being of restricted extent to permit the head of the first metatarsal and the posterior portion of the os calcis to be supported by the insole of a shoe with which said device is associated.

CHARLES P. LEYDECKER.
